UNITED STATES PATENT OFFICE

93,794

DESIGN FOR A METAL CHAIR OR SIMILAR ARTICLE

Charles F. Rauch, St. Louis, Mo.

Application October 16, 1933, Serial No. 49,491

Term of patent 7 years

To all whom it may concern:

Be it known that I, CHARLES F. RAUCH, a citizen of the United States, residing at St. Louis, in the county of St. Louis in the State of Missouri, have invented a new, original, and ornamental Design for a Metal Chair or Similar Article, of which the following is a specification, reference being had to the accompanying drawing, forming part

thereof. The figure is a perspective view of a metal chair or similar article showing my new design.

I claim:

The ornamental design for a metal chair or similar article as shown.

CHARLES F. RAUCH.
